ROLLER SKATE

Gordon K. Ware, Chicago, Ill., assignor to The Chicago Roller Skate Company, Chicago, Ill., a corporation of Illinois

Filed July 16, 1964, Ser. No. 383,128
8 Claims. (Cl. 280—11.2)

This invention relates to a novel skate structure, and more specifically to a novel roller skate structure.

As will be understood, the action and techniques involved in ice skating are frequently significantly different from those involved in roller skating primarily as the result of the fact that an ice skater balances on a relatively narrow edge of a blade and frequently only on a limited area of the blade edge while a roller skater utilizing conventionally available skates balances on a relatively broad flat platform provided by four widely spaced wheels having relatively wide flat peripheral edges. Thus persons who engage in various forms of ice skating such as racing, figure skating, ice hockey or merely pleasure skating cannot obtain the same action with conventionally available roller skates. Persons interested in ice skating usually have available to them a limited season during which they can participate in their chosen sport, which season may be controlled by the weather or the limited availability of indoor ice skating rinks.

An important object of the present invention is to provide a novel skate structure utilizing rollers or wheels constructed and arranged in a manner for simulating the action of ice skates.

A further object of the present invention is to provide a novel skate structure utilizing rollers or wheels, which structure may be adjusted for enabling a skater to simulate ice skates used for one or more activities including racing, hockey and figure skating.

Still another important object of the present invention is to provide a novel skate structure of the above-described type which may be readily adjusted for fitting a wide variety of shoe sizes.

A further object of the present invention is to provide a novel skate structure of the above-described type which is of simple, rugged and economical construction.

Other objects and advantages of the present invention will become apparent from the following description and the accompanying drawings wherein:

FIG. 1 is a side elevational view showing a skate structure incorporating features of the present invention;

FIG. 2 is a plan view of the skate structure shown in FIG. 1;

FIG. 3 is an enlarged partial sectional view taken generally along line 3—3 in FIG. 1;

FIGS. 4 and 5 are fragmentary sectional views showing the manner in which wheel elements of the skate structure function during different maneuvers;

FIG. 6 is a side elevational view showing the skate structure in a position for enabling a skater to pivot about a desired point;

FIG. 7 is a side elevational view showing a skate structure incorporating a modified form of the present invention;

FIG. 8 is a side elevational view of the skate structure shown in FIG. 7 in a tilted position for engaging a toe stop element with the floor;

FIG. 9 is a fragmentary sectional view taken generally along line 9—9 in FIG. 10;

FIG. 10 is a partial sectional view taken generally along line 10—10 in FIG. 9; and

FIG. 11 is a sectional view taken along line 11—11 in FIG. 9.

Referring now more specifically to the drawings wherein like parts are designated by the same numerals through-

2

out the various figures, a skate structure 20 incorporating features of the present invention is shown in FIGS. 1 through 6. The skate structure comprises opposite side frame means 22 and 24 which are laterally spaced apart and preferably have the general configuration and appearance of ice skate blades when viewed from the side. The side frame means 22 and 24 respectively present forward sole plate flanges 26 and 28 and heel plate flanges 30 and 32 adapted to be riveted or otherwise secured to a shoe of known construction, not shown. If desired suitable clamping means, not shown, could be assembled with the sole and heel plate flanges for detachably connecting the skate structure to a shoe.

The side frame means 22 comprises forward and rear frame members presenting longitudinally extending and overlapping blade-like portions 34 and 36. Strut portions 38 extend upwardly from the blade portion 34 for supporting the sole plate flange 26 and similar upstanding strut portions 40 extend from the blade portion 36 to the heel plate flange 30. The side frame means 24 is substantially identically but oppositely constructed and includes overlapping front and rear blade portions 42 and 44 and forward upstanding strut portions 46 supporting the sole plate flange 28 and rearwardly disposed upstanding strut portions 48 supporting the heel flange 32.

The skate structure 20 includes a plurality of rollers or wheels 50, 52, 54, and 56 which are all arranged in a straight line in a space 58 between the side frame means 22 and 24. The wheels are respectively mounted on axles 60, 62, 64, and 66 extending between the side frame means and through apertures therein as will be described more fully below. The wheels are all of uniform size, shape and structure so that they may be interchanged if desired.

As shown best in FIG. 3, each of the wheels comprises an annular disc 68 formed of tough, firm but slightly soft and resilient rubber. The outer periphery 70 of the wheel disc 68 has a substantially semicircular cross-sectional configuration and the inner periphery is mounted on a hub 72 having axially spaced annular surfaces 74 and 76 for cooperative engagement with annular series of ball bearings 78 and 80. The bearings are retained by telescoping and interconnected cone elements 82 and 84.

The axle 62 extends through the cone elements 82 and 84 and has an enlarged head 86 at one end thereof and is adapted to receive a nut member 88 at its opposite ends for securing the parts in assembled relationship. It is to be noted that the cone elements 82 and 84 have integral portions 90 and 92 projecting beyond opposite sides of the narrow wheel disc 68 for engaging inner surfaces of the opposite frame structures and maintaining predetermined spaces or clearances 94 and 96 between the wheel disc and the side frame means. As previously indicated the remaining wheels are identical to the wheel 52 and therefore need not be described in detail.

In order to accommodate the axles of the wheels, the side frame means 22 and 24 are provided with aligned apertures as shown best in FIGS. 1 and 6. More specifically the apertures are closely and preferably substantially uniformly spaced along the length of the side frame means 22 and 24 for permitting adjustment of the location of the wheels for purposes mentioned below and the apertures are arranged into three groups of apertures 98, 100 and 102. In the embodiment shown, there are six apertures 98 (98—1 through 98—6) adjacent forward ends of the side frame means 22 and 24, four apertures 102 (102—1 through 102—4) adjacent rear ends of the side frame means and remaining apertures 100 are arranged between the forward and rear groups.

It is important to note that the apertures 100 are formed so that their axes are disposed in a first horizontal plane while the apertures 98 and 102 are located so that

their axes are disposed above the axes of the apertures 100. In this embodiment the axes of apertures 98-1, 98-2 and 98-3 are disposed substantially in a second plane inclined with respect to the first mentioned horizontal plane so that these apertures are progressively higher in a rearward direction. The apertures 98-4 and 98-5 are preferably in the same horizontal plane as the aperture 98-3. The apertures 101-1, 102-2 and 102-3 are also in an inclined plane, but this plane is disposed so that these apertures progressively increase in height from the trailing end of the skate forwardly. The aperture 102-4 is preferably in the same horizontal plane as the aperture 102-3.

The peripheries of the intermediate wheels 52 and 54 project downwardly the same distance since the axles of these wheels extend through apertures 100. Furthermore, the peripheries of the intermediate wheels 52 and 54 project below the peripheries of the opposite end wheels 50 and 56 since the axles of the wheels 50 and 56 respectively extend through apertures 98 and 102. With this arrangement only two of the wheels will engage the ground or floor at any one time so that during a skating motion a slight rocking action will be obtained which will simulate the action of ice skates which are frequently curved at least slightly upwardly adjacent forward and rear ends thereof. The amount of rocking action may be adjusted by changing the location of the end wheels 50 and 56 in the apertures 98 and 100 for raising or lowering the end wheels with respect to the intermediate wheels. The arrangement is such that upon tilting the skates slightly as shown in FIG. 6, only the wheel 52 will engage the ground for enabling the skater to pivot about the single point of engagement provided by the wheel 52. Again, this action is much the same as can be obtained on ice skates.

As previously indicated and as shown best in FIG. 3, the wheels are formed so that their peripheral edges have a semicircular cross-sectional configuration. Also as previously indicated, the material from which the wheels 68 are formed is tough and firm, yet resiliently yieldable or soft. More specifically it has been found that the rubber material from which the wheels are made preferably has a hardness which may be measured by a Durometer and falls between about 85 on the Durometer A scale and 57 on the Durometer D scale. This enables the rubber wheels to resist flattening sufficiently to roll easily and smoothly while at the same time it enables the peripheral edges of the wheels to flatten slightly under the weight of a skater for providing a flat spot 104 as shown in FIGS. 4 and 5 for promoting sufficient frictional engagement or gripping of the floor to resist undue lateral sliding. It will be observed that the flat spot 104 has a width similar in width to conventional ice-skating blades for enabling the skate structure further to simulate the action and feel of an ice skate. The semicircular configuration of the peripheral edge enables the flat spot 104 to move freely across the skate wheel as the skater tilts the skate between the vertical position shown in FIG. 4 and an inclined position such as that shown in FIG. 5.

As previously indicated, the holes 98, 100 and 102 are preferably uniformly spaced along the opposite side frames 22 and 24. This arrangement permits the overall length of the skate structure to be freely adjusted by removing the intermediate wheels and the axles 62 and 64 and relatively longitudinally shifting the forward and rear portions of the side frame means relative to each other. When the portions of the side frame means have been adjusted in a desired manner the intermediate wheels are reassembled. Since the axles of the wheels provide the only means securing the side frames together, the front and rear portions of the side frame means may be freely adjusted relative to each other and the increments of such adjustments are limited only by the spacing of the apertures.

The front and back wheels 50 and 56 may be adjusted relative to the intermediate wheels for changing the operating characteristics of the skate structure in accordance with the desires of a particular skater and in accordance with the intended use of the skate. For example when it is desired to simulate the relatively long blade of a racing skate, the wheels should be spaced apart a maximum distance as shown in FIGS. 1 and 6. On the other hand, if it is desired to simulate the action of the relatively short blades of figure skates or hockey skates, one or both of the front and rear wheels 50 and 56 may be moved to positions closer to the intermediate wheels and, if desired, the intermediate wheels may be moved to positions closer together.

During a skating action and particularly when making turns or jumps, the forces applied to the tough but resilient rubber wheels will cause the wheels to twist relative to their axles and the side frame means 22 and 24. In order to prevent the wheels from rubbing against the side frame means during said twisting, the aforementioned extensions 90 and 92 of the wheel bearing cones are constructed so as to cause the spaces 94 and 96 between the wheels and the side frames to be substantial and preferably to be at least about one-fourth as great as the radial distance of the wheel disc 68 between the hub members 72 and the semicircular marginal portions 70. This arrangement has been found sufficient to prevent interference between the wheels and the side frame means without unduly increasing the overall width of the frame structure.

As shown best in FIG. 2, the rear portions 36 and 44 of the opposite side frame means are adapted to extend along outer surfaces of the forward portions 42 and 44. Furthermore, the wheels 50, 52 and 54 are normally positioned between the inner surfaces of the portions 34 and 42 while the rear wheel 56 is positioned between inner surfaces of the rear frame means portions 36 and 44. In order to permit the same wheel to be used in all positions, sections 106 and 108 of the frame means portions 44 and 46 are offset inwardly for presenting inner sides or surfaces thereof in the same planes as the inner sides or surfaces of the forward frame means portions 34 and 42. Thus the aforementioned desired clearances are provided between the offset portions 106 and 108 and the rear wheel 56 while at the same time the extensions 90 and 92 of the bearing cone engage the inner surfaces of the frame means sections 106 and 108 in the same manner as the corresponding bearing cones of the forwardly positioned wheels engage the inner surfaces of the side frame means portions 34 and 42.

In FIGS. 6 through 10 a modified embodiment of the present invention is shown, which embodiment is similar to the structure described above as indicated by the application of identical reference numerals with a suffix *a* added to corresponding elements. This embodiment differs in that the apertures 98a are successively progressively increasingly offset above the horizontal plane containing the axes of the apertures 100a in a direction extending from the apertures 100a toward the forward end of the skate structure. In addition, the apertures 102a are successively and progressively increasingly offset outwardly from the apertures 100a in a direction extending toward the rear end of the skate. In other words, the axes of the apertures 98a and 102a are respectively disposed in planes inclined upwardly from the horizontal plane containing axes of the apertures 100a. With this arrangement, the skate structure 20a will provide for a uniform rocking action as the forward and rear wheels are adjusted between successive apertures 98a and 102a. In other words, the same amount of inclination of the skate structure is required for engaging the wheels 50a and 52a simultaneously against the ground when the axle of the wheel 50a extends through the aperture 98a closest to the apertures 100a as when the axle extends through the outermost aperture 98a.

The skate structure 20a also includes a toe stop assembly 110. However, it is to be understood that a similar toe stop assembly may be incorporated in the skate structure of the previously described embodiment, if desired.

The toe stop assembly 110 comprises a friction member 112 molded of rubber or any other suitable material around metal inserts 114 and 116. The inserts 114 and 116 are adapted to embrace the forward ends of the side frame portions 34a and 42a. Apertures 118 and 120 are provided through the inserts 114 and 116 and are located for alignment with one of the apertures 98a in the opposite side frames and faced rearwardly of the forwardmost aperture 98a. Fastening means 122 and 124 in the form of rivets or screws and complementary nuts extend through the apertures 118 and 120 and the aligned apertures in the side frame means for pivotally securing the toe stop assembly to the side frame means. As shown in FIG. 10 inner ends of the fastening means 122 and 124 are respectively substantially flush with the inner surfaces of the side frame means for permitting the wheel 50a to be adjusted forwardly from the position shown without interference from the fastening means 122 and 124.

As shown in FIGS. 9 and 10 the inserts 114 and 116 have arcuate portions 126 and 128 having the common axis of the apertures 118 and 120 as their centers of curvature and presenting inner surfaces engageable with the extreme outer ends of the frame means portions 34a and 42a. Thus the frame means portions provide rigid abutments engageable with and backing up the inserts of the toe stop member while at the same time the toe stop structure may be pivoted about the axis of the apertures 118 and 120 for adjusting an eccentric portion 130 of the friction member 112 toward or away from the floor. In order to secure the toe stop assembly in a desired adjusted position, a bolt 132 extends through the forwardmost aperture 98a in the opposite side frame means and also through arcuate slots 134 and 136 in the inserts 114 and 116. A nut 138 is assembled with the bolt and is adapted to be tightened for clamping the toe stop assembly in the desired adjusted position. It will be observed that when the skate is tilted in the manner shown in FIG. 8 the toe stop friction member is engaged against the floor. The degree to which the skate structure must be tilted for accomplishing such an engagement may be changed by adjusting the position of the toe stop friction member.

While the preferred embodiments of the present invention have been shown and described herein, it is obvious that many structural details may be changed without departing from the spirit and scope of the appended claims.

The invention is claimed as follows:

1. A skate structure comprising spaced apart longitudinally extending opposite side frame means respectively including overlapping relatively adjustable forward and rear longitudinally extending portions, said opposite side frame means having a first group of aligned apertures therein adjacent a forward end thereof, a second group of aligned apertures therein intermediate opposite ends thereof, and a third group of aligned apertures therein adjacent a rear end thereof, said apertures being spaced from each other longitudinally of said frame means, a

plurality of wheels disposed between said opposite side frame means and spaced longitudinally thereof, and axle means extending through aligned apertures in said opposite side frame means and through said wheels and supporting said wheels and securing said opposite side frame means together, certain of said axle means extending through apertures in overlapping parts of said forward and rear portions of the side frame means and providing the only means connecting the forward and rear portions together.

2. A skate structure, as defined in claim 1, wherein at least two of said axle means extend through spaced sets of aligned apertures in the overlapping parts of the forward and rear portions of the opposite side frame means.

3. A skate structure, as defined in claim 1, wherein the apertures of said second group of apertures are disposed with their axes substantially in a first generally horizontal plane and the apertures of said first and third group of apertures are disposed with their axes in planes offset upwardly from said first mentioned plane.

4. A skate structure, as defined in claim 3, wherein said last mentioned planes are inclined upwardly and respectively rearwardly and forwardly from said first plane.

5. A skate structure, as defined in claim 3, wherein said last mentioned planes are inclined upwardly and respectively forwardly and rearwardly from said first mentioned plane.

6. A skate structure, as defined in claim 1, which includes a stop member of tough, resilient friction material mounted on forward ends of said opposite side frame means.

7. A skate structure, as defined in claim 6, which includes means adjustably securing said stop member on said side frame means for selectively positioning the stop member at different elevations.

8. A skate structure, as defined in claim 1, wherein each of said wheels comprises a hub portion and an annular disc of firm, tough and resilient material on said hub portion, said disc of each of said wheels having a peripheral edge portion of rounded cross section and a predetermined radial extent between said peripheral edge portion and its associated hub portion, said skate structure including means extending between said wheels and said opposite side frame means and maintaining clearances between said opposite side frame means and said discs of the wheels for preventing interference between the wheel discs and the side frame means in the event of deflection of the wheel discs under skating conditions, and each of said means maintaining said clearances having a width equal to about one-fourth of said radial extent of the wheel discs.
